Patented at the
Scientific American
PATENT OFFICE
1853

Julius E. Merriman, of Meriden, Conn.
Letters Patent No. 582. Dated July 26th 1853.

The schedule referred to in these Letters Patent and making part of the same

To all whom it may concern:

Be it known that I, Julius E. Merriman, of Meriden, in the County of New Haven, and State of Connecticut, have invented a new and useful Ornamental Design for a Lady's Sewing Bird. And I do hereby declare that the following is a full clear and exact description of the same reference being had particularly to the accompanying drawings forming part of this specification, in which,

Fig: 1. is a plan of a sewing bird at rest, ornamented after my Design.

Fig: 2. is a side elevation of the same.

Fig: 3. is a profile view of the sewing bird at rest.

The same letters of reference in each of the several Figs indicate corresponding parts.

This invention consists principally in the design of a sewing bird at rest and in the ornamental configuration of the same.

The wings of the bird A, as seen in Fig: 1, particularly, are handsomely ornamented with feathers B, B, and the back near the tail is also handsomely feathered, the feathered wings D, D, being shown at rest and crooked over the tail C, which is also handsomely feathered as seen in Fig: 1. There is also an ornamental embellishment C, round the upper bill of the bird.

This design of a bird at rest and ornamented presents a fine and neat appearance and renders it more suitable for the purpose intended.

What I claim as my invention and desire to secure by Letters Patent, is

The Design & Configuration of the Sewing Bird at rest, as herein described & represented in the accompanying drawings.
